ARTHUR R. ENQUIST, OF MERIDEN, CONNECTICUT, ASSIGNEE TO FOSTER, MERRIAM & COMPANY, OF MERIDEN, CONNECTICUT, A CORPORATION OF CONNECTICUT.

LOCKING-LATCH.

1,241,613.

Specification of Letters Patent.

Patented Oct. 2, 1917.

Application filed December 20, 1916. Serial No. 137,994.

To all whom it may concern:

Be it known that I, ARTHUR R. ENQUIST, a citizen of the United States, residing at Meriden, county of New Haven, State of Connecticut, have invented an Improvement in Locking-Latches, of which the following is a specification.

This invention relates to the class of locking-latches adapted for general use and especially adapted for use on refrigerator doors and the like, which is described and claimed in Letters Patent to Harry A. Palmer, No. 1,086,208, dated Feb. 3, 1914, in which the cost of construction and number of parts is reduced to the minimum, and the present invention has for its object a re-organization and re-arrangement of the parts of the latch in order to provide a structure that may be assembled more easily, that will work more easily, that will avoid notching and thus weakening the upper arm of the combined spring and bolt, and which will lock by rotation of the key toward the left instead of toward the right, which is desired by the trade. This I accomplish by giving to the substantially U-shaped combined spring and bolt a relatively wide bend, which gives freer spring action, and placing the upper arm of said member above the key-hub instead of below it with the necessary changes in the details of construction.

In the accompanying drawing forming a part of this specification Figure 1 is a front perspective view of my novel locking-latch as in use;

Fig. 2 a rear perspective view with the cover-plate removed, the combined spring and bolt being in the locking position;

Fig. 3 a similar view with the combined spring and bolt in its normal or retracted position, leaving the latch operative;

Fig. 4 a perspective view of the combined spring and bolt detached, and

Fig. 5 an elevation of the latch detached.

10 denotes the case which is provided with flanges having holes for attaching screws and a cover-plate, not shown, which rests on posts in the case, said case having a chamber to receive the operating parts. 13 denotes 50 the latch which is pivoted on a stud 14 projecting from the case and is provided with a tail-piece 15 and an upwardly projecting arm 16 which lies within the case and covers the slot 17, through which the operative end

of the latch projects. The latch is operated 55 by means of a lever 18 pivoted outside the case and having an operating arm 19 which projects through a slot 20 in the case and engages the tail-piece of the latch.

21 denotes the slideable combined spring 60 and bolt which is substantially U-shaped and comprises an upper arm 22 and a lower arm 23, said spring and bolt being preferably formed of flat resilient material. The upper arm is provided with a locking projection 24, formed in the present instance by making a V-shaped bend in the arm, and with a key-receiving socket 25 formed by making another V-shaped bend in the arm. The lower arm is suitably shaped to bear 65 upon the top of the latch at a suitable distance from its pivotal point, being formed with a portion extending substantially at right angles to the arm 22, for a substantial distance, and then extended in a continuous 70 curve to the latch. The combined spring and bolt is retained in place by studs 26, 27 and 28, the former lying in the bend of the spring and below the upper arm, and the others lying above said arm. The combined 75 spring and bolt is yieldingly retained against movement in either direction when in the unlocked position, by the engagement of the projections or bends of the upper arm with lugs 27 and 28, as clearly shown in 80 Fig. 3, and when in the locked position it is yieldingly retained against backward movement by engagement of the locking projection with stud 28, as clearly shown in 85 Fig. 2. Just within arm 16 of the latch and 90 above the body of the latch, is a stud 29 which is received in a recess 30 in the latch when the latter is raised.

31 denotes a key-hole in the case and 32 a key-hub which is adapted to oscillate in 95 the case and cover plate (not shown) the ends of said hub being mounted in the usual manner in holes in the case and cover plate. A bit of the key (not shown) is adapted to engage the key-receiving socket 100 in the combined spring and bolt to move said member into and out of the locking position. The key hub 32 is staggered with respect to the studs 27 and 28, and said hub extends from the front wall of the case in 105 such position as to co-operate with the studs to guide the upper arm 22 in its sliding movements. The studs 27 and 28 project

from one of the marginal walls of the lock chamber, above said hub.

The operation is as follows:—When the combined spring and bolt is in its retracted or unlocking position as in Fig. 3, the lower arm simply serves as a spring to retain the latch in place. The operative end of the latch is shown as beveled to engage a keeper (not shown) and be raised in the usual manner against the power of the spring, or the latch may be raised against the power of the spring by operation of the lever. To lock the latch the key is inserted in the hub and the hub rotated thereby toward the left as seen in Fig. 1, or toward the right as seen in Fig. 3. A bit of the key will engage the key-receiving socket in the combined spring and bolt and will force said member toward the left, or toward the right as seen in Fig. 3 (which is a reverse view), the locking projection passing under stud 28 and then rising through the resiliency of the arm on the opposite side of the lug, as in Fig. 3, and retaining the member in that position until it is retracted by operation of the key. The locking is effected by passing the end of the lower arm of the combined spring and bolt under lug 29, as clearly shown in Fig. 2, said arm covering recess 30 in the latch and lying between the latch and the stud, thus making it impossible to raise the latch. Unlocking of the latch is effected by a reverse movement of the key-hub by means of the key, which can only be removed when the hub is either in the locking or the unlocking position. In unlocking, the hub is rotated toward the right as seen in Fig. 1 or toward the left as seen in Fig. 2, a bit of the key engaging the key-receiving socket in the combined spring and bolt. This leaves the latch free to be operated by the lever or by slamming

the door to which the case is attached to the closed position.

Having thus described my invention, I 45 claim:—

1. A lock of the character described comprising a case provided with a chamber, studs projecting from one marginal wall of said chamber, a key hub projecting from the front wall of said chamber and staggered with respect to said studs, a latch, and a resilient locking member having a straight arm slidably mounted between and guided by said studs and said key hub, said locking member also having a curved arm bearing against said latch, said straight arm having a locking projection coöperating with one of said studs and also having a bend forming a key-engaging recess. 60

2. A lock of the character described comprising a case provided with a chamber, studs projecting from one marginal wall of said chamber, a key hub projecting from the front wall of the chamber and staggered with respect to said studs, a latch, and a resilient locking member formed of flat resilient material, having a straight arm slidably mounted between and guided by said studs and said key hub, said locking member also having an arm provided with a portion at right angles with the straight portion and integral therewith, said angularly disposed portion extending from the straight arm a substantial distance and terminating in a continuously curved arm bearing against said latch, said straight arm having bends forming a locking projection and a key-engaging recess, respectively, said locking projection coöperating with 80 one of the said studs. 70

In testimony whereof I affix my signature.

ARTHUR R. ENQUIST.
